UNITED STATES PATENT OFFICE.

HENRY W. STEDLER, OF BOSTON, MASSACHUSETTS.

BOOT OR SHOE.

1,130,854.

Specification of Letters Patent.

Patented Mar. 9, 1915.

Application filed August 21, 1913. Serial No. 785,899.

To all whom it may concern:

Be it known that I, HENRY W. STEDLER, a subject of the King of Prussia and German Emperor, and a resident of Boston, in the county of Suffolk and State of Massachusetts, have invented certain new and useful Improvements in Boots or Shoes, of which the following is a specification.

On account of certain conditions now existing, the supply of leather suitable for use in making the soles of boots and shoes seems to be decreasing with a consequent increase in cost to the consumer. Hence, in the manufacture of boots and shoes, there is 15 an increased cost of production and the raising of prices to the ultimate purchaser.

The exposed part of the sole, which may include the forepart and the shank, should be made of high grade sole leather, but the 20 quality of the leather forming that part of the sole which is covered and protected from wear, for instance the part which is covered by the heel, need not be of the highest, for reasons which are apparent to any one.

According to my invention, I cut that portion of the sole, which is exposed, out of sole leather of a high grade or quality, and that part of the sole, which is covered, out of a cheap and low quality of leather. These 25 two pieces of leather have abutting edges or surfaces which are preferably perpendicular to the plane of the sole, and they are secured together by stitches which are preferably concealed in channels cut for the purpose adjacent said edges. In this way, the 30 two portions of the sole are positively connected at a point where the joint is covered by a protecting layer, as for instance a sole tap or a heel.

On the drawing.—Figure 1 represents a shoe embodying the invention. Fig. 2 shows the exposed portion of the sole which is made of high grade sole leather. Fig. 3 shows the joint or connection between the 35 two portions of the sole. Fig. 4 is a section on the line 4—4 of Fig. 3.

The shoe may be, so far as its general construction is concerned, either a Goodyear welt or a McKay shoe. The sole consists of 40 the two portions or parts, which in this embodiment of the invention constitute respectively the forepart and shank, as at 5, and the heel part, as at 6. The part 5 is made of sole leather of a good quality, whereas the 45 part 6 is made of some cheaper portion of the hide which could not ordinarily be used.

Preferably the two parts of the sole should be about the same in thickness. The two parts have abutting or confronting edges which meet on a line located between the breast 60 and the rear of the edge of the heel 7, as shown in Fig. 1, so that, when the heel is nailed in place, the joint is completely covered and concealed. Adjacent the transverse edges of the parts 5 and 6, said parts 65 are channeled by a suitable instrument to receive the stitches which unite the parts. By a suitable sewing machine, the abutting edges are sewed together by a line of stitches 70 located in the bottoms of the channels, as shown in Figs. 3 and 4. The stitches may be of the lock or chain variety, and they lie in a plane parallel to and intermediate the surfaces of the sole. Preferably the stitches are drawn taut so as to hold the abutting 75 edges closely together, and, when the shoe is subjected to the waxing and finishing operations, the line of separation of the edge is substantially completely concealed. The flaps of the channel may be cemented in place 80 after the stitching operation and before the heel is secured in place. Preferably the channels are cut in the flesh side or upper face of the parts of the sole, and they are covered by the inner sole 9.

By the construction herein described, the shank of the shoe, which generally should be flexible, is intact and its flexibility unimpaired, it being formed of leather of high grade, as is the entire exposed portion of the 90 sole in the shoe shown. If the shoe is to be provided with a tap covering the forepart, the toe end of the forepart may be formed of leather of a poor or cheap grade, and united to the remainder of the forepart by 95 a line of stitches or other fastenings located in channels, such joint being covered and concealed by the tap when the shoe is completed. I would not consider it a departure 100 from my invention if fastenings, other than the form shown, were used,—say for instance staples or the like.

From the foregoing description it will be seen that, notwithstanding the increased cost of high grade sole leather, I am able 105 to produce a sole, the cost of which is relatively low, since a material part thereof is made of cheap material, and yet which possesses manufacturing properties, wearing qualities and attractive appearance equal to 110 a one-piece sole of high grade. The sole, notwithstanding that it is made in two

pieces, is continuous from toe to heel, and affords a complete layer of proper thickness. By cutting the edges square, or perpendicular to the face of the sole, I save more stock than if the edges were overlapping.

What I claim is:—

1. As a new article of manufacture, a shoe sole consisting of a plurality of portions having abutting edges, and stitches located entirely between the faces of the sole and connecting said abutting edges together.
2. As a new article of manufacture, a shoe sole consisting of a plurality of portions having abutting edges, said portions having channels parallel to and adjacent said edges, and a line of stitches located in said channels and connecting said abutting edges.
3. As a new article of manufacture, an outer sole for boots and shoes, the same comprising complementary portions having abutting edges, all the portion of said sole, which is to be exposed when the boot or shoe having the sole is completed, being formed of a single piece of relatively high grade leather and the remainder of said sole being formed of cheap or low grade leather, and fastenings located entirely between the faces of said sole for securing the abutting edges together.
4. A boot or shoe having an outer sole consisting of a plurality of parts with abutting edges transverse to the length of the sole and perpendicular to the faces thereof, stitches located entirely between the faces of the sole for securing said abutting edges together, and means exterior to said sole for covering said abutting edges.
5. A boot or shoe having a sole consisting

of a plurality of parts formed of relatively high grade and low grade leather respectively, said parts having transverse perpendicular abutting edges with adjacent channels, fastenings located in said channels between the surfaces of the sole for securing said edges together, and means exterior to said sole and secured thereto and overlapping said abutting edges and channels.

6. A boot or shoe having a sole consisting of a plurality of parts formed of relatively high grade and low grade leather respectively, said parts having transverse abutting edges with parallel adjacent channels, fastenings located in said channels between the surfaces of the sole for securing said edges together, and means exterior to said sole and secured thereto, said means completely covering the sole part made of the inferior leather and overlapping and concealing the butting edges and channels.

7. A boot or shoe having a sole consisting of a plurality of parts formed of relatively high grade and low grade leather respectively, said parts having transverse abutting edges with parallel adjacent channels, fastenings located in said channels between the surfaces of the sole for securing said edges together, and a heel secured to said sole and completely covering the face of the sole part formed of inferior leather and overlapping the part formed of higher grade leather so as to conceal the channels and abutting edges of said parts.

In testimony whereof I have affixed my signature, in presence of two witnesses.

HENRY W. STEDLER.
